UNITED STATES PATENT OFFICE.

WILLIAM ELIOT BARROWS, OF PHILADELPHIA, PENNSYLVANIA, AS-SIGNOR TO THE WELSBACH LIGHT COMPANY, OF GLOUCESTER CITY, NEW JERSEY.

DESIGN FOR A GAS-LIGHT GALLERY.

SPECIFICATION forming part of Design No. 25,807, dated July 21, 1896.

Application filed May 14, 1896. Serial No. 591,584. Term of patent 14 years.

To all whom it may concern:

Be it known that I, WILLIAM ELIOT BARROWS, a citizen of the United States, residing at the city of Philadelphia, in the county of Philadelphia and State of Pennsylvania, have invented and produced a new and original Design for Incandescent Gas-Light Galleries, of which the following, taken in connection with the accompanying drawings, is a specification.

My design relates to an impression, ornament, or pattern to be stamped or otherwise placed on or worked into that part of an incandescent gas-light which is usually superposed on the air-shutter and carries the globe, and which is commonly designated the "gallery."

The impression, ornament, or pattern which constitutes my design is coroniform and is composed of a circle or fillet *a*, having on the edge dentiform fretwork *b*, of which the frets comprise conventionalized lotus-leaves *c*,

fern *d*, and oak-leaves *e*, combined together for the production of a curvilinear contour or outline and of openings. This impression, ²⁵ ornament, or pattern may obviously be wrought in brass, gold-plate or other metal or composition of metals and may be increased or decreased in size. The leading feature of my design may be said to be the coroniform ³⁰ gallery provided with dentiform open fret-work ornamented with and composed of a combination of frets substantially as described and shown.

What I claim as new, and desire to secure ³⁵ by Letters Patent, is—

The design for an incandescent gas-light gallery, substantially as shown.

In testimony whereof I have hereunto signed my name.

WILLIAM ELIOT BARROWS.

In presence of—

F. H. MAC MORRIS,
THOS. A. JAMES.
